UNITED STATES PATENT OFFICE.

WILLIAM S. AUCHINCLOSS, OF PHILADELPHIA, PENNSYLVANIA.

ORDER-BOOK.

SPECIFICATION forming part of Letters Patent No. 268,599, dated December 5, 1882.

Application filed July 31, 1882. (No model.)

To all whom it may concern:

Be it known that I, WILLIAM S. AUCHINCLOSS, a citizen of the United States, residing at Philadelphia, in the county of Philadelphia and State of Pennsylvania, have invented new and useful Improvements in Order-Books, of which the following is a specification.

This invention relates to an order-book which is composed of a series of stub-sections for recording the orders, and a series of order-sections composed of postal-cards, for transmitting the orders, each stub-section being provided with an address tag or label which extends from said stub-section over the face of one of the order-sections or postal-cards, and serves to unite the postal-card or order-section with its stub-section.

In the accompanying drawings, Figure 1 represents a plan of my order-book when the same is opened. Fig. 2 is a face view of one of the order-sections or postal-cards detached from its stub-section and ready for mailing.

Similar letters indicate corresponding parts.

In the drawings, the letter A designates my order-book, each leaf of which is composed of a stub-section, *a*, and an order-section, *b*. The stub-section serves to record the order intended to be forwarded by the corresponding order-section, and it is preferably provided with a schedule or table for facilitating the operation of recording; but, if desired, the stub-sections may be left blank, so that the entire order must be recorded in writing. The order-section *b* consists of a postal-card, which is intended to contain on one side the address of the party or firm to whom the order is to be given, and which has room on its other side for the order. From the stub-section *a* extends an address tag or label *c*, which is provided 40 with paste, gum, or other adhesive substance on its under surface, and so formed that it can

be readily brought over the address-side of the postal-card and pasted thereon, thereby retaining the postal-card in its place, as shown in Fig. 1 of the drawings. On the face of the address-tag is printed or otherwise produced the address of the party to whom the orders are to be transmitted. Along the connecting-line, between the address-tag and the stub-section, are a series of perforations, so that when an order has been written on the order side of the postal-card *b* and recorded on the stub-section *a*, Fig. 1, the postal-card can be torn off and mailed without further delay. When the postal-card is torn off it carries with it the address-tag *c*, Fig. 2. The combined postal-cards and stubs can, however, be used loosely and without being bound in book-form.

What I claim as new, and desire to secure by Letters Patent, is—

1. An order-book which is composed of a series of stub-sections for recording the orders, and a series of order-sections composed of postal-cards for transmitting the orders, each stub-section being provided with an address tag or label, which extends from said stub-section over the face of one of the postal-cards or order-sections, and serves to unite the postal-card or order-section with its stub-section, substantially as shown and described.

2. The combination, with a memorandum-blank having an address-tag, of a postal-card, substantially as hereinbefore shown and described.

In testimony whereof I have hereunto set my hand and seal in the presence of two subscribing witnesses.

WM. S. AUCHINCLOSS. [L. S.]
